UNITED STATES PATENT OFFICE.

CHARLES ALBERT TATUM, OF NEW YORK, N. Y., ASSIGNOR TO WHITALL,
TATUM & CO., OF PHILADELPHIA, PENNSYLVANIA.

DESIGN FOR A BOTTLE-STOPPER.

SPECIFICATION forming part of Design No. 15,120 dated July 1, 1884.

Application filed January 31, 1884. Term of patent 7 years.

To all whom it may concern:

Be it known that I, CHARLES ALBERT TATUM, a citizen of the United States, and a resident of New York city, New York, have invented or produced a new and original Design for a Bottle-Stopper, of which the following is a specification.

My design for the top of a bottle-stopper is fully illustrated in and by the accompanying drawings, in which Figure 1 is a side view; Fig. 2 an end view, and Fig. 3 a top view.

My design is restricted to the top A of the stopper from the neck *a* upward, this top being of the quadrangular form shown, and being studded on all five faces with pyramidal

projections, as clearly indicated in the drawings.

I claim--

The design for a bottle-stopper, the same being of quadrangular form and studded on all five sides with pyramidal projections, substantially as shown.

In testimony whereof I have signed my name to this specification in the presence of two subscribing witnesses.

CHAS. A. TATUM.
